CLAIM

The ornamental design for a brush handle and head unit, as shown and described.

DESCRIPTION

FIG. 1 is a top front perspective view of a brush handle and head unit showing our new design;

FIG. 2 is a front elevational view thereof;

FIG. 3 is a right side elevational view thereof, the left side being a mirror image;

FIG. 4 is a rear elevational view thereof;

FIG. 5 is a top plan view thereof; and,

FIG. 6 is a bottom plan view.

Outlines of the bristles are shown in broken lines in the figures for illustrative purposes only and do not form part of the design claimed.

FIG. 2

FIG. 3

FIG. 5

FIG. 4

FIG. 6
